UNITED STATES PATENT OFFICE.

WILLIAM D. HAINES, OF DELAWARE, NEW JERSEY.

MARKING, COVERING, AND FURROWING MACHINE.

SPECIFICATION forming part of Letters Patent No. 618,413, dated January 31, 1899.

Application filed May 6, 1898. Serial No. 679,893. (No model.)

To all whom it may concern:

Be it known that I, WILLIAM D. HAINES, a citizen of the United States, residing in Delaware township, in the county of Camden and State of New Jersey, have invented a new and useful Agricultural Machine for Marking, Furrowing, and Covering, of which the following is a specification.

Reference is had to the accompanying sheet 10 of drawings, making part of this specification, in which—

Figure 1 is a side elevation, Fig. 2 is a plan view, and Fig. 3 is a sectioned view, of one of the disks.

15 Similar letters refer to similar parts in the several views.

A is the fixed and perforated single axle of the machine, B the ground-wheels, and C the draft-pole-hanging strip of the fixed axle A, 20 which is carried horizontally from the axle by the parallel bars a, braced by the cross-bars b. Hinged to the draft-pole-hanging strip C is the tailpiece D of the draft-pole E, adapted for one or more horses.

25 F is a vertical post of the draft-pole-hanging strip C, and G a vertical post of the draft-pole E.

H is a perforated marking-pole pivoted to the draft-pole at c, so as to assume a vertical 30 or horizontal position, as circumstances may require, and I its supporting-brace from the draft-pole E.

J is a hand-lever pivoted at its bottom end to the post F of the hanging-strip C and 35 midway of its length to a rod K, whose opposite end is pivoted to the post G of the draft-pole E. Said lever J has a hand-trip e, in engagement with a notched bar L, pivoted to the post G and capable of engaging with a 40 cross-pin of the post F by its rod g.

M are forked carrying-arms which are fixed to and extend rearwardly from the axle A, embracing the ground-wheels B, and at their outer ends are provided with bolting-plates 45 h, through which pass the screw ends of hangers i, of carrying-disks N, revolving by means of a stud i', fixed to the hub k of each disk and journaled in the bottom end of each hanger i.

O is a perforated cross-bar of the draft-pole E, through which pass the screw ends of 50 the forward hangers i.

When furrowing, the disks N at the rear concave inwardly and swivel with their hangers i. For covering, said disks are detached from their hangers and connected with the 55 front hangers i', as at N', of the perforated cross-bar O at the front, with the difference that the concavity of each disk N' faces inwardly or to each other.

As shown, the machine has but one lever 60 J, which is moved by the operator, riding on the seat P, elevating or depressing the hanging-strip C and the draft-pole tailpiece D around the hinge j. The marking-pole is not double and extensible, but consists of a single 65 piece provided with perforations k', into which is fitted the furrow-marking pin l.

I claim—

1. In a furrower and coverer, the combination of a single perforated fixed axle, adjustable ground-wheels, draft-pole-hanging strip fixed to said axle, draft-pole tailpiece hinged to the draft-pole-hanging strip, draft-pole, vertical post of the draft-pole-hanging strip, vertical post of the draft-pole, notched lever 75 between said vertical posts, hinged latch-lever, and vibrating arm between the latch-lever and the vertical post of draft-pole.

2. In a furrower and coverer, the combination of a single perforated fixed axle, adjustable ground-wheels, rearwardly-projecting disk-carrying arms, depending hangers of the disk-carrying arms, disks provided with fixed carrying-studs which revolve with them and turn in bearings at the bottom of their depending hangers, marking-pole, means for supporting said marking-pole, tracing-pin, draft-pole, perforated cross-bar of the draft-pole, and covering-disks of the perforated cross-bar.

In testimony whereof I affix my signature in presence of two witnesses.

WILLIAM D. HAINES.

Witnesses:

FRANCIS D. PASTORIUS,
B. D. ARCHER.
